Application filed August 25, 1881. Term of patent 3½ years.

To all whom it may concern:

Be it known that I, EDUARD LEISSNÈR, of New York, in the county and State of New York, have invented a new and original Design for Wall-Papers and Similar Fabrics, of which the following is a specification.

This invention relates to a new design for wall-paper and similar fabrics; and it consists in the novel grouping and configuration of parts hereinafter more fully described.

The accompanying photograph illustrates a face view of a wall-paper bearing my new design.

An ornamental base, B, is surmounted by a

cross, E, above which is a fanciful figure, e, flanked on each side by fanciful figures e. At the sides of the figure B are the four-leaf figures G G; above these, ball-shaped ornaments b, and near the latter the fanciful figure F.

I claim—
